CASIN W. OBERT, OF MOUNT VERNON, NEW YORK.

STEAM BOILER.

Application filed August 1, 1924. Serial No. 729,431.

This invention relates to steam boilers and has for one of its objects to provide an improved arrangement of the water tubes and fire tubes with a certain circulation of the products of combustion whereby the heat units generated from the fuel consumed are utilized to a maximum degree in the conversion of the water into steam.

In one embodiment of my present improvements I provide water-circulating tubes in the firebox, extending longitudinally over the fire from the lower portion of the rear water leg, forward to the upper portion of the front water leg, which in connection with the main boiler heating surface comprising the usual plurality of longitudinal fire tubes extending longitudinally above the crown sheet from the rear head to the front head of the boiler, combine in a novel and improved form both fire-tube boiler characteristics and water tube boiler characteristics. This combination, particularly on account of the direct and uninterrupted exposure of the furnace water tubes to the radiant heat of the fire, causes a great rapidity of water circulation in these water tubes from the lower portion of the rear water leg where the coolest water in the boiler normally settles, up and into the upper portion of the front water leg, and gives a new arrangement of water circulation in the entire boiler interior, whereby the contents of the fire-tube boiler portion above the crown sheet is kept constantly stirred and moving from the front to the rear portions, in counter-flow to the flow of the gases from the points of coolest gases to the hottest gases. With this circulation arrangement, no stagnant water pockets can exist in any portion of the boiler and every part of the fire tubes above the crown sheet is thoroughly scoured by the water circulating rapidly out of the furnace water tubes. This obviously improves the rate and increases the amount of heat transfer of the boiler, and tends toward increased efficiency and capacity when in operation.

While either of these two principal elements have heretofore been extensively used separately in boiler construction, their combination in this arrangement provides a boiler of increased capacity and efficiency and constitutes an important practical improvement in the art. Such a combination

of parts produces also a new co-operation 55 thereof and a new result.

Another important feature of this new and improved design of boiler is the design of furnace which occupies the entire length of the fire box from front to rear water leg, 60 with crown sheet the entire length, and the application of the grate into one end thereof only, so as to constitute not more than from 50 to 75 per cent of the furnace area, which affords a new and heretofore unused 65 proportion of furnace volume to grate area. This is claimed as an important improvement in furnace construction, because, the long gas and flame travel in the furnace insures a full and complete combustion of the 70 fuel and gases before they reach the end furnace plates or the tubes, and before they are cooled thereby so as to cause smoke.

In addition, the water circulation tubes in the furnace are especially shaped so as to support a fire brick arch over the fire, for use with bituminous coal, which in combination with the above juxtaposition of fire tubes and water tubes constitutes a practical 75 improvement in the art. The fire brick 80 arch which is exposed directly to the fire, becomes highly heated and incandescent therefrom and by virtue of this retained heat which is reflected back to the fuel bed as the gases flow in increased length of 85 travel, rapidly kindles fresh fuel, when applied, and brings about complete combustion and freedom from smoke.

Therefore, the elements of my invention 90 comprise the counterflow actions of combustion gases and water to be heated, the combination of furnace water tubes and fire tubes above a longitudinally extending crown sheet, a fire box of full length of boiler and providing ample combustion 95 space, and in event of use of bituminous coal, a fire brick arch that increases the length of gas travel and insures completeness of combustion.

It is a further general object of the invention to provide a steam boiler of the above character which is a very economical construction and the several novel features thereof are susceptible of use in connection with stationary, marine or locomotive 105 boilers.

With the above and other objects in view, the invention consists in the improved steam

boiler and its construction and arrangement of its several parts as will be hereinafter more fully described, illustrated in the accompanying drawings and subsequently incorporated in the subjoined claim.

In the drawings, wherein I have illustrated one simple and satisfactory embodiment of the invention and in which similar reference characters designate corresponding parts throughout the several views,—

Fig. 1 is a vertical longitudinal section through a steam boiler showing one form of my present improvements, said section being taken substantially on the line 1—1 of Fig. 2;

Fig. 2 is a transverse section taken on the line 2—2 of Fig. 1.

Referring to the drawings, the outer body shell 5 of the boiler and the inner shell 6 thereof are arranged in spaced relation to each other and in conjunction therewith there are provided front and rear water legs 7 and 8 respectively, communicating with the side water legs 9. The inner and outer shells 5 and 6 are connected at their forward ends to provide the fuel feed opening 10, said shells being also connected at their rear ends by the tubular member 11 which provides a passage opening into the rear chamber 12.

The fire-box 13 of the boiler is provided with the usual grate 14 of any preferred construction which supports the fuel bed. At the rear side of the fire-box a transverse bridge wall 15 is arranged and provides an intermediate support for a series of longitudinally extending water tubes 16. The rear ends of these water tubes communicate with the lower end of the rear water leg 8, said tubes extending forwardly and upwardly at a gradual inclination and being connected at their forward ends to the upper end of the front water leg 7.

Above the crown sheet 17 of the inner shell 6 a plurality of parallel fire tubes 18 are arranged and communicate at their rear ends with the chamber 12 and at their forward ends with the outlet flow 19 which is in communication with the stack leading to the atmosphere.

The top wall of the outer shell 5 of the boiler is provided with a suitable opening 20 for the connection of a steam outlet pipe 20^a thereto.

In the operation of the boiler as above described, it will be understood that the coldest water will seek the lowest level in the water legs. These water legs, the tube 16 and the space above the crown sheet 17 to a point above the uppermost fire tubes 18 is completely filled with water, and as the water in the tube 16 extending over the fire-box 13 becomes highly heated, it flows upwardly through said tubes, the relatively cold water entering the rear ends of the tubes from the water leg 8. The hot water is, therefore, con-

tinually delivered into the upper end of the front water leg 7. The flame and products of combustion, after impinging upon the water tubes 16 pass rearwardly through the tube 11 into the chamber 12 and into the rear ends 70

of the fire tubes 18 as indicated by the arrows in Fig. 1 of the drawings. It will, therefore, be evident that the relatively high heat of the flame and products of combustion will also be radiated through the wall of the tube 75

11 and the rear ends of the fire tubes and such heat absorbed by the relatively cool water passing downwardly around said tubes into the rear water leg 8. After the products of combustion are drawn forwardly through 80

the fire tubes 18, the temperature thereof gradually decreases by the absorption of heat by the walls of said tubes and transmission thereof to the water surrounding said fire tubes so that when the products of combustion reach the forward ends of said tubes 85

and pass into the outlet 19 they will be at a comparatively low temperature, and at this point substantially no heat would be given up by the gases to the water, since the water at this point delivered from the upper forward ends of the tubes 16 is at its highest temperature. The distinction between my present improvements and the ordinary 90

steam boiler is thus clearly evident. In the latter the products of combustion pass from the boiler furnace to the outlet flow at the point where the water is of a relatively low temperature, and only the initial heat of the products of combustion is utilized to its full- 95

est extent. In the arrangement above described, it will be seen that the coldest water is subjected to the highest heat of the flame and products of combustion so that the water will be more quickly heated and to a relatively higher temperature than in the present type of furnace with the same fuel consumption. It will also be noted that the flow of the gases and water counter each other. Also, the efficiency of the boiler is materially increased by arranging the fire tubes 18 directly above the crown sheet 17. Thus heat will be radiated from the crown sheet and absorbed by the water immediately 100

above the same and surrounding the fire tubes 18 so that water above the crown sheet will at all times be at a substantially uniform high temperature and will not have any appreciable cooling effect upon the fire tubes.

The water circulating tubes 16 in the furnace extend longitudinally over the fire from the lower portion of rear water leg 8, forward to the upper portion of the front water leg 7. There is, therefore, a great rapidity of water circulation in these water tubes from the lower portion of the rear water leg 8, where the coolest water normally settles, up and into the upper portion of the front water leg 7. A novel circulation 115

120

125

130

is thereby produced, in that, among other things, the contents of the boiler above the crown sheet is kept constantly stirred and moving from the front to the rear portion, in counterflow to the flow of the gases.

The boiler 5 itself, occupies the entire length of the fire box from the front to the rear water leg, with the crown sheet 17 the entire length therebetween. The grate occupies only one end thereof, not more than 50 to 75 per cent of the furnace area. The long travel of the fuel and gases insures a full and complete combustion of the fuel and gases before they reach the end furnace plates, or the tubes, and before they are cooled and develop smoke.

The tubes 16 are shaped by being bent in a curve, as shown in Fig. 1, and preferably so as to support a fire brick arch 30 over the fire, especially adapted for bituminous coal. This arch 30 becomes highly heated and incandescent, and its retained heat is reflected back to the fuel bed, and rapidly kindles fresh fuel.

From the foregoing description considered in connection with the accompanying drawings, the construction and manner of operation of my improved steam boiler will be clearly understood. In the particular combination and arrangement of the parts, as above described, I have succeeded in materially increasing the operating efficiency of such boilers. It is possible, that the advantageous results of this new combination might be obtained in other detail constructions of the various elements and slightly different arrangements thereof, and therefore, since the several novel features of my present disclosure might be exemplified by other mechanical constructions, it is to be understood that I reserve the privilege of resorting to all such legitimate changes in the form, proportion and relative arrange-

ment of the several parts as may be fairly embodied with the spirit and scope of the invention as claimed.

What I claim is:

A steam boiler comprising: a tubular boiler proper; a front water leg and a rear water leg arranged at and substantially flush with the front end respectively with the rear end of the tubular boiler; a crown sheet on the tubular boiler; a plurality of comparatively narrow tubes for the combustion gas extending through the tubular boiler above the crown sheet; a fire box below the front end of the crown sheet; a combustion chamber below the other end of the crown sheet; a gas reversing box extending outside of the rear end of the tubular boiler and communicating with the before-mentioned gas tubes; a passage through the rear water leg, connecting the combustion chamber with the gas reversing box; a gas collecting chamber at the front or exit end of the gas tubes at the outside of the tubular boiler; a single row of spaced comparatively large water circulating tubes, connecting the lowest part of the rear water leg with the upper part of the front water leg and passing through both the fire box and the combustion chamber; a separating wall between the fire box and the combustion chamber extending from the ground up to the row of water circulating tubes; a firebrick arch extending from the separating wall along the upper side of the water circulating tubes upwardly for a limited length, adapted to force the flames of the fire box against the uppermost part of the water circulating tubes and to reflect some heat back to the fuel on the furnace grate.

In testimony that I claim the foregoing as my invention, I have signed my name hereto.

CASIN W. OBERT.
